UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI, A CORPORATION.

EXTENSIBLE LEG-REST FOR CAR-SEATS.

No. 926,309.

Specification of Letters Patent.

Patented June 29, 1909.

Application filed January 12, 1909. Serial No. 471,832.

To all whom it may concern:

Be it known that I, HUBERT WITTE, a citizen of the United States of America, residing at the city of St. Louis, in the State of Missouri, have invented certain new and useful Improvements in Extensible Leg-Rests for Car-Seats, of which the following is a full, clear, and exact description, reference being had to the accompanying drawings, forming 10 part of this specification.

My invention relates to a leg rest for car seats that is adapted to be extended from a position beneath the cushion of the seat and to either side of the seat, or to be retracted 15 from an extended position so that when not in use the parts of the leg rest will occupy positions beneath the car seat cushion.

Figure I is a top or plan view of the framework of a car seat and my leg rest, the leg 20 rest being shown in extended position. Fig. II is in part an end elevation and in part a vertical cross section of a car seat with my leg rest shown in extended position. Fig. III is a view similar to Fig. II with the leg 25 rest in retracted position. Fig. IV is a view partly in side elevation, and partly in vertical longitudinal section of the car seat framework and my leg rest, the leg rest being shown in retracted position. Fig. V is an 30 enlarged top or plan view of one of the runway bearers, its hangers, and one of the bars of the leg rest. Fig. VI is a vertical cross 35 section taken on line VI—VI Fig. V, and looking in the direction of the arrow crossing said line. Fig. VII is a vertical cross section taken on the line VII—VII Fig. V, and looking in the direction of the arrow crossing said line.

In the accompanying drawings: 1 designates one of the pedestals of a car seat and 2 are longitudinal right angle frame bars supported by said pedestals. The frame bars 2 serve as supports for other members entering 45 into the general construction of the car seat to which my present invention does not pertain, and also as supports for the members of my leg rest which is the subject matter of this application.

3 designates runway bearers extending 50 transversely of the framework of the car seat. These runway bearers are supported by hangers 4, which are in turn supported by the frame bars 2 and are preferably cast integral with the runway bearers. Each runway 55 bearer is provided with a lower guard

flange 5 and an upper guard flange 6 extending longitudinally of the bearer, and between which is a runway 7 that receives a main extensible leg rest supporting member to be more particularly referred to in the following 60 description.

Above the guard flange 6 of each runway bearer and fixed either to the bearer or one of its hangers is a short stop arm 8 that is provided with a leg 9 projecting downwardly 35 alongside of and adjacent to the upper guard flange 6 of the bearer, (see Figs. I, II, V, and VI.) Fixed to each runway bearer, or one of its hangers above its upper guard flange and remote from the stop arm 8 is a long stop 70 arm 10, (see Figs. I, II, IV, V, and VII,) that juts outwardly from the upper guard flange and has a downwardly extending leg 11 that is separated from the upper guard flange to provide a gap 12 between the leg and upper 75 guard flange. The utility of the stop arms 8 and 10 will hereinafter appear.

13 designates main extensible leg rest supporting bars that are provided at their outer sides with longitudinal ribs 14 operable in the 80 runways 7 of the runway bearers 3. Each extensible leg rest supporting bar is provided at its inner side with a runway 15 that is produced by a lower flange 16 and an upper flange 17, both extending longitudinally of 85 the bar. Extending upwardly from each extensible leg rest supporting bar 13 and at or near one of its ends is a stop lug 18 that is located adjacent to the upper guard flange 6 and is adapted to move through the gap 12 90 between said upper guard flange and the leg 11 of the stop arm 10 and to be brought into engagement with the leg 9 of the stop arm 8 when the extensible leg rest supporting bar is moved transversely of the car seat and extended beyond one side of said seat. At the end of each extensible leg rest supporting bar, opposite that at which the stop lug 18 is located, is a stop lug 19 that is located at a greater distance from the runway bearer 3 100 than the stop lug 18, and which is adapted to move in a path in which it will not engage the stop arm 8, but is adapted to engage the leg 11 of the stop arm 10 when the leg rest supporting bar is moved transversely of the car 105 seat and in a direction opposite to that previously referred to.

It will be seen that by the construction just described, the stop lugs 18 and 19 serve to restrict the degree to which the extensible 110

leg rest supporting bars may be moved in either one direction or an opposite direction, and that the construction provides for this service without interference between the stop 5 lugs and the stop arms that are respectively intended for engagement with each other.

It will be observed by referring to Fig. I that the stop arms 8 and 10 are alternated in positions upon the two runway bearers 3; 10 that is, the stop lug 8 upon one bearer is located at one side of the seat, and opposite to it on the other bearer is a stop arm 10, and at the opposite side of the seat the runway bearer that is provided with the stop arm 8 15 has associated with it a stop arm 10, while the other runway bearer has associated with it at said side a stop arm 8. It will also be observed that the stop lugs 18 and 19 are so located in alternating positions upon the pair 20 of extensible leg rest members 13 as to provide for the lug 18 engaging the stop arm 8 and the stop lug 19 engaging the stop arm 10 at the side of the seat from which the leg rest supporting bars are extended.

25 The main extensible leg rest supporting bars 13 are connected by cross rods 20, (see Figs. I to IV, inclusive,) and serve as supports for a leg rest that is extensibly and pivotally fitted to said bars. This leg rest comprises a pair of side bars 21 provided with 30 gudgeons 22 that are slidably fitted in the runways 15 in the bars 13 and are connected by a leg rest board 23. Each side bar of the leg rest is provided at its outer side with a 35 pair of flanges 24 that extend longitudinally of the side bar and are adapted to rest and ride upon the bars 13 when the leg rest is moved longitudinally of said bars. The flanges 24 extend inwardly from the ends of 40 the foot rest side bars and gaps exist between the inner ends of the flanges, as seen in Fig. I, to permit the tilting of the leg rest into the position seen in Fig. II, when the leg rest and the extensible supporting bars 13 are in extended positions. The supporting bars 13 45 are adapted to occupy positions above the supporting frame of the car seat when the leg rest is not in use, and the foot rest, including its side bars, at this time occupies a position 50 above the supporting bars, as seen in Figs. III and IV.

For the purpose of preventing movement of the foot rest supporting bars and the foot rest when they are in restricted positions 55 above the car seat frame and beneath its cushion, I provide dogs 25 pivoted at 26 to

the ends of the runway bearers 3 and which are provided with arms 27 that are adapted to extend across the ends of the foot rest supporting bars 13, as seen in Figs. III and IV, 60 to hold the bars 13 from longitudinal movement.

I claim:—

1. In a leg rest attachment for car seats, the combination of runway bearers, each runway bearer being formed with a lower guard flange, and an upper guard flange, providing a runway between them, main extensible leg rest supporting bars, each supporting bar being formed with a rib at its outer side, operable in a runway bearer and with a lower flange and an upper flange on its inner side providing a runway, cross rods connecting the supporting bars, and a leg rest comprising a pair of side bars provided with gudgeons 75 operable in the runways at the inner sides of the leg rest supporting bars, each side bar being provided at its outer side with a pair of aligned flanges, spaced apart, providing gaps between them and riding upon the supporting bars and a leg rest board connecting the side bars.

2. In a leg rest attachment for car seats, the combination of runway bearers, extension bars operable in said runway bearers 85 and provided with stop lugs, and stop arms associated with said runway bearers and adapted to be engaged by said stop lugs when the extension bars are moved to an extended position at either side of the car seat; said 90 stop lugs being offset from each other upon each extension bar.

3. In a leg rest attachment for car seats, the combination of runway bearers, extension bars operable in said runway bearers 95 and provided with stop lugs, and stop arms associated with said runway bearers and adapted to be engaged by said stop lugs when the extension bars are moved to an extended position at either side of the car seat; 100 said stop lugs being offset from each other upon each extension bar and one of the stop arms associated with each runway bearer being so constructed as to permit the passage of one of the stop lugs therethrough to permit its movement to the stop arm at the opposite side of the seat.

HUBERT WITTE.

In the presence of—

M. O. MURPHY,
E. P. CHITTENDEN.
